United States Patent Office.

GIDEON E. NEWCOMB, OF BUCKSPORT, MAINE.

Letters Patent No. 102,961, dated May 10, 1870.

IMPROVED BOOT AND SHOE-HEEL.

The Schedule referred to in these Letters Patent and making part of the same.

To all whom it may concern:

Be it known that I, GIDEON E. NEWCOMB, of Bucksport, in the county of Hancock and State of Maine, have invented a new and useful or Improved Heel for Boots and Shoes; and I do hereby declare that the following, taken in connection with the drawings which accompany and form part of this specification, is a description of my invention sufficient to enable those skilled in the art to which it appertains to practice it.

This invention relates to an improvement in hollow metallic heels; and

The invention consists in an improved method of constructing the heel, it being made in two parts, an upper and an under section; an improved method of securing the heel to the boot or shoe; and also in providing the heel with spurs or calks, which may be projected through the bottom, or withdrawn, at the pleasure of the wearer, as will be hereinafter more fully described.

Figure 1 is a perspective view of the under side of the upper section;

Figure 2 is a perspective view of the under section in its proper position;

Figure 3 is a vertical section taken longitudinally through the boot-sole, and showing a section thereof; and

Figure 4 is a perspective view of my invention complete.

Similar letters indicate corresponding parts in the several figures.

In the drawings—

A represents the upper, and

B the under section of the heel.

The upper section is formed with a thin flange, a, inside of which fits the flange b, formed upon lower section B.

These two flanges, thus fitting closely together, hold the two sections in their proper relative positions, or to prevent lateral movement; while, for the

purpose of locking them closely together, a short spur, d, is formed upon the section B, at the rear part, which fits into a corresponding recess in section A; and a spring, e, secured at its lower end to section B, as shown in fig. 3, catches into a recess in section A, thus firmly locking the two sections together.

To separate the sections, a pointed instrument or awl is inserted in a small aperture between the sections, and pressed against spring e, forcing it out of the recess in section A, when they are readily separated.

g is a flange formed upon section A, inside of the bearing f, and perforated with holes h, in which are inserted screws, by which the heel is secured to the sole C.

c e are pointed screws, fitted in threaded holes in section B, as shown in fig. 3, and which, when extended through the heel-bottom, serve as calks when the streets are icy, and, when not required, they are readily turned back, after section B is removed from the boot.

Among the advantages of my invention are, the ease and security with which it is attached to the boot or shoe, its simplicity, cheapness, and durability, and the ease with which it is changed from a smooth to a calked heel, and back again, at the will of the wearer.

Having thus described my invention,

What I claim as new, and desire to secure by Letters Patent, is—

1. In combination with a divided heel, the adjustable calks e e, substantially as and for the purposes specified.

2. The combination of sections A B, spur d, and spring e, with their holding recesses, substantially as and for the purposes specified.

GIDEON E. NEWCOMB.
